CLAIM

The ornamental design for a direct sample collection pad, as shown and described herein.

DESCRIPTION

FIG. 1 is a top view of an embodiment of a direct sample collection pad in accordance with our new design.

FIG. 2 is a top right perspective view of the direct sample collection pad of FIG. 1.

FIG. 3 is a bottom view of the direct sample collection pad of FIG. 1.

FIG. 4 is a left view of the direct sample collection pad of FIG. 1.

FIG. 5 is a left perspective view of the direct sample collection pad of FIG. 1.

FIG. 6 is a right view of the direct sample collection pad of FIG. 1.

FIG. 7 is a right perspective view of the direct sample collection pad of FIG. 1.

FIG. 8 is a top front perspective view of the direct sample collection pad of FIG. 1.

FIG. 9 is a front view of the direct sample collection pad of FIG. 1.

FIG. 10 is a top rear view of the direct sample collection pad of FIG. 1; and,

FIG. 11 is a back view of the direct sample collection pad of FIG. 1.

The broken lines depict portions of the direct sample collection pad form no part of the claimed design.
